UNITED STATES PATENT OFFICE.

ALBERT F. PRESTON, OF LYNN, ASSIGNOR TO THE PRESTON MACHINE COMPANY, OF BOSTON, MASSACHUSETTS.

MACHINE FOR STRETCHING UPERS OF BOOTS OR SHOES.

SPECIFICATION forming part of Letters Patent No. 325,567, dated September 1, 1885.

Application filed January 31, 1885. (No model.)

To all whom it may concern:

Be it known that I, ALBERT F. PRESTON, of Lynn, in the county of Essex and State of Massachusetts, have invented certain new and useful Improvements in Machines for Stretching the Uppers of Boots and Shoes, of which the following is a full, clear, and exact description.

This invention has for its object the stretching of that portion of the upper of a boot or shoe called the "shank" preparatory to the lasting of the same, and for the better fit of the upper at such place to the foot of the wearer; and the invention consists, in substance, of two series of clamps or jaws arranged in horizontal and parallel planes, one series above the other, in combination with suitable mechanism for operation on said clamps or jaws to cause them to firmly grasp and hold between them the upper of a boot or shoe, and to then move the outer clamps or jaws of each series in a direction to stretch such upper, substantially as hereinafter fully described.

In the accompanying plate of drawings is illustrated a machine constructed and arranged for operation on the upper of a boot or shoe in accordance with this invention.

Figure 1 is a front view. Fig. 2 is an end view of the working parts with the frame-work in section. Fig. 3 is a vertical cross-section on line 3 3, Figs. 1 and 4, looking to the right, and showing a portion in side elevation. Fig. 4 is a horizontal section on line 4 4, Fig. 1, and showing in dotted lines an upper of a boot or shoe in position for operation thereon. Fig. 5 is a similar view to Fig. 4, but showing the parts in different positions. Fig. 6 is a horizontal section on line 6 6, Fig. 1, and Fig. 7 is a detail sectional view.

In the drawings, A represents a frame-work composed of a bed-plate, B, and a top plate, C, connected together by bars D, all of metal, or any suitable material, and on which are supported and carried the working parts of the machine.

E and F are two uprights adapted by their ends *a* to turn in sockets in the plates B C, and each having two horizontal arms, G H, projecting forward therefrom, one, G, above the other, H, and between these arms of each upright E F are secured, respectively, rods

J K. The rods J K carry two jaws, L M and N P, connected to their respective rods J K by sockets *d*, by which they are adapted to turn on said rods horizontally, and the two lower ones, M P, to move up and down thereon.

Q is a jaw in the same horizontal plane with and between the jaws L N, and attached by its end *e* to a vertical rod, R, secured by its upper end, *f*, in the plate C, the lower end, *g*, of the rod extending down into an opening, *h*, in the plate B.

S is another jaw below the jaw Q in the same horizontal plane with and between the jaws M P, and attached to the rod R by a socket, *l*, fitting over the rod R, and having a spline-joint, *m*, to prevent the jaw from swiveling on its rod and yet allow it to move up and down thereon.

The jaws L, Q, and N constitute the upper series, and the jaws M, S, and P the lower series, and their ends *n* extend out beyond the front of the frame-work for convenience in use when operating the machine.

The upper series of jaws are connected together on their upper sides at their front ends, *n*, by two horizontal bars, T U, by screws *p*, the bars overlapping each other at the middle jaw, Q, one of the screws *p* passing through the two bars, T U, and screwing into said jaw, and the jaws of the lower series are connected together at their front ends on their under sides by similar bars, V W, by screws *q*, the bars overlapping each other at the middle jaw, S, and one of the screws *q* passing through both bars V W and screwing into the jaw S. The screws *p* *q* serve as pivots on which the jaws can swivel in the operation of the machine.

The upper middle jaw, Q, is rigidly secured to the rod R, and holds the jaws L N in the same horizontal plane by its connection therewith by the bars T U, although they can be held in such position in any suitable manner and independent of the jaw Q.

X and Y are two collars or sleeves, respectively on the rods J K, below the jaws, and adapted to freely move up and down thereon.

Z is an arm or rod, its upper end, *r*, extending up through the opening *h* in the plate B, and having at such end *r* an open socket, *t*,

into which the lower end, g , of the post or rod R projects.

u is a spiral spring encircling the rod R , and resting on the upper end of the rod Z and between it and the jaw S .

v w are two flat bars, connected at their lower ends by screws y to the front of said rod Z , and extending thence, as shown, upwardly through openings a' in the plate B , and connected at their upper ends by screws b' to the front side of the collars X Y , respectively.

c' d' are two similar flat bars, connected at their lower ends by screws f' to the back side of the rod Z , and extending upward through openings g' in the bed-plate and attached to the collars X Y on the opposite side to the bars v w by screws h' .

The upper surface, t' , of each of the lower jaws, M S P , is corrugated or serrated longitudinally, as shown in Fig. 6 more particularly, and the under surface, m' , of the two upper outer jaws, L N , is similarly corrugated or serrated a portion of their length, as shown at n' in Fig. 2, the other portion, p' , of the surface being smooth.

The corrugations of the upper and lower jaws mesh together, and when so meshed the outer edges, q' , of the corrugations on the under jaws bear on the smooth part p' of the upper jaws.

The machine is shown in its normal position as ready for operation in Figs. 1, 2, 3, 4, and 6, and its operation is substantially as follows: The two sides of an upper of a boot or shoe having been sewed together in the usual manner, one of the sides at its edge—for example, at the shank portion—is placed between the two series of jaws, the face side of the material uppermost, and with the seam, if 35 the side is formed of two parts, between the middle jaws, as described, and substantially as shown in dotted lines in Fig. 4. The arm or rod Z is then forced upward in any suitable manner, which compresses the spring u , raises 40 the middle jaw, S , and by its connection with the collars X Y , the lower outer jaws, M P , to and against and firmly closes the two series of 45 jaws upon the side of the boot-upper between them, and then swings the arms G H outwardly 50 on their pivots a , which carry with them the inner ends, r' , of the said outer jaws, swinging 55 said jaws into the positions shown in Fig. 5, whereby the unclamped portions of the side of the boot or shoe upper between the outer 60 jaws and the middle jaws will be pulled and stretched at and about the edge and back therefrom accordingly. Lowering the arm or rod Z , the outer jaws are moved toward their respective middle jaws, and the lower series of 65 jaws fall away from the upper series of jaws, leaving the boot or shoe upper free to be removed therefrom, and the other side of the upper or another upper placed in and operated upon by the machine, as before.

65 The upper middle jaw, Q , has a central longitudinal rib, t^2 , of T shape in cross-section,

the portion u' of which lies within a shoulder, v' , in the jaw to prevent escape therefrom, the portion w' projecting through an opening, x' , in the lower face of the jaw.

z' is a piece of rubber between the portion u' of the rib t' and the inside of the shoulder, which acts as a spring upon the rib. This rib t' is for the purpose of securing, in connection with the face of the jaw at either side 75 of said rib a strong and continuous hold on the upper, each side of the stitching forming the seam of the upper of the boot or shoe, as shown in detail cross-section in Fig. 7, which represents the two parts A' B' of an upper of 80 a boot or shoe secured together by the stitches a^2 and placed between the two jaws Q S , the portion b^2 of the jaw bearing on the two thicknesses A' B' of material and the rib t' on the under thickness. By this means a firm and 85 even grip of the two parts at such seam outside and independent of the stitches is secured, thereby preventing injury to the stitches by relieving them of all strain when stretching the upper. The rubber spring allows for varying thicknesses of the parts by its yield, and yet it is of sufficient power to firmly press the rib against the material between it and the lower jaw.

Any suitable spring can be used—such as a 95 flat steel spring properly inserted—also the spring can be dispensed with and the rib made integral with or as a part of the jaw or rigidly attached thereto, and also can extend to one side of the jaw; but it is preferable to have it yielding, as in such case various thicknesses 100 of uppers of boots or shoes can be satisfactorily operated upon, and it is also preferable to have the rib centrally arranged, as shown, as it can operate upon the right or left side of 105 a seam of the upper.

The stretching of the shank of an upper of a boot or shoe in such a machine is secured easily and quickly and at one operation, the stretch being the most at the edge and substantially in the arc of a circle and gradually diminishing from the edge toward the portion of the upper where grasped by the outer ends, n , of the jaws, or substantially of fan-shape.

The corrugations or serrations on the jaws 115 enable the jaws to more firmly grasp and hold the upper between them so it will not slip, and as the upper jaws bear upon the face side of the material the corrugations thereon are shortened, as shown, so as not to extend onto 120 that part of the upper not lasted to the sole.

The post or rod Z has a shoulder, f^2 , against which the lower end, g , of the rod R can abut if desired, to limit the movement of the rod Z and thus the jaws.

This machine can be used to stretch other parts of the upper to a boot or shoe, as is obvious.

The frame-work can be supported upon any suitable table or support, and the arm or rod Z can be connected to any suitable lever or treadle for operating it.

Having thus fully described my invention, what I claim as new, and desire to secure by Letters Patent, is—

1. In a machine for stretching the upper 5 of a boot or shoe, two series of jaws adapted to grasp and hold between them the boot or shoe upper, each outer jaw of each series being adapted by mechanism, substantially as described, to move laterally in a circular direction from and toward the middle jaw of its series, in combination with a rod or arm suitably connected to said jaws for operation thereof, substantially as described.

2. In a machine for stretching the upper of 15 a boot or shoe, two series of jaws adapted to grasp and hold between them the boot or shoe upper, each outer jaw of each series being adapted by mechanism, substantially as described, to swing or turn laterally upon a 20 pivot or center at one end from and toward the middle jaw of its series, and at the other end to swing or turn upon a swinging arm, in combination with a rod or arm connected to said jaws for operation thereof, substantially 25 as described.

3. In a machine for stretching the upper of a boot or shoe, two series of jaws adapted to grasp and hold between them the boot or shoe upper, each outer jaw of each series being 30 adapted by mechanism, substantially as described, to swing or swivel laterally from and toward the middle jaw of its series, upon a pivot or center at one end on a bar or arm connected to said middle jaw and at its other end 35 to swing or swivel upon a swinging arm, in combination with a rod or arm connected to said jaws, for operation thereof, substantially as described.

4. In a machine for stretching the upper of 40 a boot or shoe, the combination, with two series of jaws, the jaws of each series being connected together, and the outer jaws of each series being connected to and arranged to turn

upon swinging arms G H, of a push-rod, Z, connected to said swinging arms, and a spring, 45 u, for operation substantially as and for the purpose specified.

5. In a machine for stretching the upper of a boot or shoe, in combination with two series of jaws, the jaws of each series being connected together, respectively, by arms T U and V W, and the outer jaws of each series being connected to and arranged to turn upon swinging arms G H, a push-rod, Z, connected by arms v w c' d' to collars X Y, respectively, upon 50 said swinging arms, and having a spring, u, substantially as and for the purpose specified.

6. The combination, with a jaw, S, of a jaw, Q, having a rib or projection, t', said jaws 60 being suitably constructed and arranged to clamp and hold between them the upper of a boot or shoe, substantially as and for the purpose specified.

7. The combination of a jaw, S, with a jaw, 65 Q, having a longitudinal central rib or projection, t', said jaws being suitably connected and arranged to clamp and hold between them the upper of a boot or shoe, substantially as and for the purpose specified.

8. The combination, with a jaw, S, of a jaw, Q, having a longitudinal central groove or shoulder, v', a rib, t', having a shoulder, w', to fit said groove, and a spring, z', said jaws being suitably constructed and arranged to clamp 75 and hold between them the upper of a boot or shoe, substantially as and for the purpose specified.

In testimony whereof I have hereunto set my hand in the presence of two subscribing witnesses.

ALBERT F. PRESTON.
